UNITED STATES PATENT OFFICE.

JOHN N. EDWARDS, OF DECATUR, ILLINOIS.

DRAFT AND EXHAUST REGULATING MEANS.

Application filed June 12, 1924. Serial No. 719,650.

This invention relates to improvements in draft and exhaust regulating means and is particularly adapted for application to steam boiler and engine installations.

5 The object of my invention is to provide means of this character which may be applied to locomotive or other mechanisms, and which will permit either automatic or manual control of an auxiliary exhaust passage or passages.

In the present day locomotive construction the steam exhausting from the cylinder and valve chests passes through an exhaust nozzle located beneath the stack so that the exhaust steam is utilized to increase the draft through the firebox. When the pressure of the steam in the boiler approximates the permitted maximum above which the safety valve is set to blow off, the use of the locomotive may serve to greatly enhance the draft, although obviously at such a time it would be advantageous to decrease the draft and thereby avoid waste of steam through blow off of the safety valve. Then, too, the provision of 20 added exhaust sectional area operable at the option of the engineer will increase the efficiency of operation, especially when climbing grades or starting under heavy load, or in short where the expansive action of the steam 25 cannot be fully utilized.

The above and other objects will be more fully described and set forth in the following specification and shown in the accompanying drawings, in which—

35 Fig. 1 is a front elevation of a locomotive showing my auxiliary exhaust ducts applied thereto, the view being toward the front of the locomotive.

40 Fig. 2 is a side elevation of apparatus embodying my invention, a portion of the locomotive being indicated in outline.

Fig. 3 is a vertical section through what I term the automatic control valve.

45 Fig. 4 is a section through one of the exhaust valves.

Fig. 5 is a section through the pop valve.

Like numerals refer to like elements throughout the drawings.

I have indicated more or less diagrammatically and in outline in Figs. 1 and 2 a typical locomotive having the cylinders 10 and valve chests 11. Located in the smoke chamber is the nozzle 15 indicated in dotted lines in Fig. 1, to which lead the exhaust ducts 16 from the valve chests 11. Located above the nozzle 15 is the stack 17. Tapped into each

exhaust passage is an exhaust valve 20 shown in an enlarged section in Fig. 4.

These exhaust valves are constructed with a main poppet valve 20^a mounted upon stem 20^b which has the boss 20^x at the valve back. The valve 20^a normally seats on valve seat 20^o to close an auxiliary exhaust duct 21 attached to the elbow portion 20^e in suitable manner. Near the upper portion of the exhaust valve 20 casing 20^f is a chamber 20^f, in which is reciprocably mounted the piston 20^g carried on the stem 20^b and smaller in effective area than the poppet valve 20^a. The coiled spring 25 extends between the upper face of piston 20^g and a centering boss 27^a of cap 27, which is threaded upon the casing 20. As will be obvious, the cap 27 may be adjusted to vary the compression of spring 25, and thereby the resistance to movement of piston 20^g. Similarly vent 27^b is provided in the cap to prevent dash-pot action upon movement of the piston 20^g. Communicating with the chamber 20^f beneath the lowermost position of piston 20^g is the inlet port 28, at which terminates the pipe 30. The partition 27^e is apertured to accommodate the stem 20^b and is recessed around the aperture to form a seat for boss 20^x at 20^h. It will be apparent that during the exhaust of steam or during any time when pressure obtains in the duct 16, this pressure will act upon the lower face of the poppet valve piston 20^g but will be overbalanced by the compression in spring 25 when below a selected point. As will be described below, 90 fluid under pressure may be applied through port 28 to overcome the pressure of the spring 25 and move valve 20^a to open position to act as an auxiliary exhaust through the duct 21, which terminates exteriorly of the stack 17. 95

Located in the cab, although this location is not necessary, is provided an automatic control valve generally indicated by numeral 35. This comprises the compound chamber having a relatively large portion 35^a and a relatively small portion 35^b. In the former is reciprocably mounted the large piston 35^c, and in the latter a relatively small piston 35^d, these pistons being joined by a single rod 35^e. The cap 35^f seals the end of the chamber 35^a, while a similar smaller cap 35^g seals the opposite end of small chamber 35^b. From the former projects a stop 35^h, and from the latter a stop 35ⁱ, these stops serving to limit the movement of the coupled pistons. An inlet port 35^k leads to one end of chamber 35^a, while from the same end of such chamber and

at the lower portion thereof is provided a drain vent 35^m of relatively small sectional area. Communicating with one end of chamber portion 35^b is the port 35ⁿ so located as 5 to lie at one side of piston 35^d regardless of the position of the latter. At the opposite side of the casing are provided the ports 35° and 35^p, at the opposite side of piston 35^d from port 35ⁿ when the piston is in shut-off 10 position. The pipe 30 terminates at port 35° and an exhaust pipe 38 depends from port 35^p opening into the atmosphere for exhaust.

A drain pipe 39 extends from casing 35 15 to any desired point and transmits the condensed steam from drain vent 35^m. A pipe or tube 40 extends from poppet valve casing 45 (described below) to port 35^k. Air or other fluid under pressure is transmitted 20 through pipe line 46 to port 35ⁿ, where it will be delivered between the pistons 35^e and 35^d. Normally the excess of area of the former will result in the coupled piston being retained in left hand position as viewed in Fig. 25 3. A branch pipe 49 extends from pipe line 46 to pipe 40, and is in communication with both, a manually operable valve 50 being provided to open or close the pipe 49.

Located upon the boiler and in connection 30 with the interior thereof is what I term the pop valve 45, comprising a casing 45^a, having the projecting boss 45^b on its top for engagement by a wrench or the like. This casing is also provided with a small vent 45^c. The 35 casing 45^a is threaded at its upper end upon the flange 45^d of the body portion. A ring 45^x is secured upon the shoulder 45^y of the main body portion by the bolts 45^z, thus providing a small chamber 45^f from which 40 leads the outlet 45^g. The upper end of the pipe 40 is connected to this outlet. The main passage 45^h in communication with the boiler is provided in the body portion of the valve and normally closed by valve 52 normally 45 seated on the valve seat 45ⁱ to close communication between the passage 45^h and chamber 45^f. The valve 52 is provided with the reduced shoulder 52^a, which extends upwardly through suitable closely fitting aperture in 50 the ring 45^d, the latter being recessed to accommodate the juncture 52^b between the shoulder 52^a and the main valve 52. Upwardly of the shoulder 52^a extends the valve stem 52^c, around which is mounted the coiled 55 compression spring 53, held in position at the upper end by the stud 45^k, depending from the inside of the casing 45^a. The casing 45^a may be adjusted relative to the ring 45^d to vary the compression in the spring 53.

60 The compression spring 53 may be adjusted to permit opening of the valve 52 at any desired steam pressure in the main boiler, for example at three pounds less than that at which the safety valve would ordinarily 65 blow off. Assuming this pressure to have

reached the point of lift of valve 52, steam will flow through passage 45^h, pipe 40, port 35^k, whereupon pressure thereof acting against the outer face of the piston 35^e will move the same to the right as viewed in Fig. 70 3. This will result in communication being provided between ports 35ⁿ and 35°, whereupon the air, preferably attached to the train supply, will flow out through port 35° to pipe 30, through port 28 into chamber 20^f beneath piston 20^g, whereupon as previously described the resistance of spring 25 will be overcome and exhaust passage 20^d in the valve 20 will be thrown in communication with exhaust pipe 21, thereby increasing the effective exhaust 80 area and reducing the flow of exhaust steam through nozzle 15 and thereby lessening the draft upon the fire.

When it is desired to open the auxiliary exhaust passages independently of the automatic control, manual valve 50 may be actuated, which will result in air under pressure flowing through pipes 49 and 40 into port 35^k which will result in the movement of pistons 35^e and 35^d to the right, which as 90 described before will permit flow of air under pressure to the exhaust valve 20 to actuate the same. This is desirable as explained in the preliminary outline hereto, as it in effect reduces the back pressure of the exhaust steam and increases the differential between the maximum and minimum steam pressure during the cycle, thereby increasing the mean effective pressure and the delivery 95 of power during the cycle.

100 While I have shown a pair of exhaust valves 20 and a pipe 21 leading from each to a common exhaust, it will be apparent that a single valve of this character can be utilized to control the auxiliary exhaust from both cylinders without departing from the spirit of my invention. Similarly it will be apparent that my invention is applicable to stationary steam engines.

I do not wish to be restricted to the form 110 shown and described except as defined in the appended claims.

What I claim is:

1. In combination a source of steam, mechanism actuated thereby, a draft nozzle, an air line, a mechanism actuatable by said steam, a main exhaust duct leading therefrom to said nozzle, an auxiliary exhaust duct leading therefrom to the atmosphere, a valve coacting with said auxiliary exhaust duct, an air duct leading from said air line to said valve, controlling means normally closing said air duct and actuatable by said steam at selected pressure to open said duct.

2. In combination a source of steam, an air line, a draft nozzle, a mechanism actuatable by said steam, a main exhaust duct leading therefrom to said nozzle, an auxiliary exhaust duct leading therefrom, a valve coacting with said auxiliary exhaust duct,

an air duct leading from said air line to said valve, controlling means normally closing said air duct and actuatable by said steam at selected pressure to open said duct, and 5 a valve manually operable to permit flow of air to said control means to actuate the same.

3. In combination with a source of steam, mechanism actuatable thereby, a draft nozzle, an exhaust passage leading from said mechanism to said nozzle, an auxiliary escape duct, a normally closed exhaust valve associated therewith, an actuating fluid supply line, a second duct leading therefrom to 10 said exhaust valve, a normally closed control valve associated with said second duct, a third duct leading from said source of steam to said control valve, a pressure-actuated valve normally closing said third duct and 15 constructed and arranged to open and remain open at or above a selected steam pressure whereby said control valve will be actuated to permit the flow of actuating fluid to said exhaust valve to open the same.

25 4. In combination with a source of steam, mechanism actuatable thereby, a draft nozzle, an exhaust passage leading from said mechanism to said nozzle, an auxiliary escape duct, a normally closed exhaust valve 30 associated therewith, an actuating fluid supply line, a second duct leading therefrom to said exhaust valve, a normally closed control valve associated with said second duct,

a third duct leading from said source of steam to said control valve, a pressure-actuated valve normally closing said third duct and 35 constructed and arranged to open at a selected pressure whereby said control valve will be actuated to permit the flow of actuating fluid to said exhaust valve to open the 40 same, and a fourth duct leading from said actuating fluid supply line to said third duct, and a manually operable valve to open and close said fourth duct whereby actuating fluid from said supply line will be supplied 45 to said control valve to actuate the same to permit the flow of actuating fluid to said exhaust valve.

5. In combination a source of steam, an air line, a mechanism actuatable by said steam, a draft nozzle, a main exhaust duct leading therefrom to said nozzle, an auxiliary exhaust duct leading therefrom, a valve coacting with said auxiliary exhaust duct, an air duct leading from said air line to said 50 valve, controlling means normally closing said air duct and actuatable by said steam at selected pressure to open said duct, and a valve manually operable to permit flow of air to said control means to actuate the 55 same, said controlling means being adjustable for actuation by said steam at different desired pressures.

In witness whereof, I hereunto subscribe my name to this specification.

JOHN N. EDWARDS.
